UNITED STATES PATENT OFFICE.

CHARLES L. FREVERT, OF MINIER, ILLINOIS.

RAILWAY-TIE.

1,005,188.

Specification of Letters Patent. Patented Oct. 10, 1911.

Application filed April 16, 1910. Serial No. 555,975.

To all whom it may concern:

Be it known that I, CHARLES L. FREVERT, a citizen of the United States, residing at Minier, in the county of Tazewell and State 5 of Illinois, have invented certain new and useful Improvements in Railway-Ties, of which the following is a specification.

This invention relates to improvements in reinforced concrete cement ties and chair 10 appliances and particularly embraces certain improvements in the constructions patented by me on Dec. 21, 1909, Patent Number 943,926.

One of the objects of the present invention is to provide improved means for securing the chair to the reinforced concrete 15 cement tie.

Another object of the invention is to improve the general structure of the reinforcing 20 means embedded in the concrete cement ties.

With the above and other objects in view the invention comprises certain combinations, 25 constructions and arrangements of parts, clearly described in the following specification and clearly illustrated in the accompanying drawings forming a part of the specification and wherein,

Figure 1 is a longitudinal sectional view 30 illustrating the improved reinforcing tie bar and the improved chair, Fig. 2 is a plan view thereof, Fig. 3 is a cross sectional view showing the construction of the chair more completely, and Fig. 4 is a plan view of one 35 of the chairs.

Referring to the accompanying drawings illustrating the invention 1 denotes a concrete cement tie in which a longitudinally disposed reinforcing metal bar 2 is em- 40 bedded. On top of the tie 1 the rail chairs 3 are positioned. These chairs are provided with depending legs 4, two of which extend from opposite sides of each chair and are connected to the reinforcing bar 2 by means 45 of transversely disposed rods or bolts 5. A portion of each leg 4 engages the side of the

bar 2 while the entire body of each leg is embedded in the concrete cement of which the tie is composed.

The method of securing the chairs to the 50 reinforcing bars effectively unites the various parts of the device so as to produce an efficient unitary structure. The chairs 3 are formed with rail engaging ribs or lugs 6, which are curved to fit the longitudinal 55 lower edge of the rail 7 and are provided with a base portion 8 which is extended laterally of the rail to engage the plate 9, which is connected to said base 8 by means of a bolt 10. The bolt 10 also serves to connect 60 the tie bar 11, which is provided with offset ends 12, whereby the central part of the tie bar will lie snugly against the upper surface of the rail tie.

By means of the improvements the va- 65 rious parts shown in the patent issued to me on Dec. 31, 1909, are more effectively united to each other and to the concrete cement tie so as to give better service. Two embedded reinforcing tie bars 2 may be employed, if 70 desired. The ends of the bar 2 are extended at 13 beyond the ends of the tie 1, whereby a series of ties may be locked together by a connecting rod passed through said ex- 75 tended ends of the tie bars 2. The other 80 constructions shown in the above patent may be employed in connection with the constructions here shown and described.

Having described my invention I claim:—

A cement tie, a tie rod embedded therein, 85 chairs having depending angular legs seated on the tie with the legs embedded in said tie, bolts connecting the legs to the tie rod, said legs being oppositely inclined, and clamping plates for the chairs.

In testimony whereof I affix my signature in presence of two witnesses.

CHARLES L. FREVERT.
